UNITED STATES PATENT OFFICE.

FRANCIS H. MILLS, OF BOSTON, MASSACHUSETTS.

BOTTLE CLOSURE.

Application filed November 10, 1921. Serial No. 514,408.

To all whom it may concern:

Be it known that I, FRANCIS H. MILLS, a citizen of the United States, residing at Boston, county of Suffolk, State of Massachusetts, have invented a certain new and useful Improvement in Bottle Closures, of which the following is a specification, reference being had therein to the accompanying drawings.

10 The invention relates to stoppers or closures for bottles and similar containers and has for its object a closure which can be readily applied to or removed from the bottle or other container. It is especially intended for use with a bottle in which the closure or stopper is to be repeatedly removed for the purpose of taking out a part of the contents and replaced to close the bottle again. The special object of the invention is to provide a stopper of such character that it can be readily tightened up after it is applied to the bottle and maintained in its tightened position until ready to be opened and then the closure can be readily loosened in order to permit it to be easily removed from the bottle.

30 The invention will be fully understood from the following description when taken in connection with the accompanying drawings, and the novel features thereof will be pointed out and defined in the claims at the close of this specification.

In the drawings, Fig. 1 is a plan view of a device embodying the invention as applied to a bottle.

Fig. 2 is a section on line 2—2 of Fig. 1.

Fig. 3 is a side elevation of the device, detached from the bottle.

Fig. 4 is a plan view of the closure member before being connected with the clamping member.

Fig. 5 is a side elevation of the metallic disk which is to be used with the cushion pad.

45 Fig. 6 is a plan view of the disk shown in Fig. 5.

Referring now to the drawings, at 1 is shown the upper portion of a bottle having a rim or bead 2 around the top of the neck 50 of well-known form of construction. The device embodies essentially two main members, namely, a stopper or cap member A and a clamping member B. The stopper member A consists of a cap 3 having a 55 downwardly extending peripheral flange 4, thus forming a sort of a cup in which

is seated a compressible cushion 5, preferably of rubber, made in the form of a disk and which when the closure is applied to a bottle, as shown in Figure 2, covers the top of the bottle. In the preferred form of construction, as shown in Figure 2, there is provided a metallic disk 6 introduced between the inside face of the cap and the rubber cushion, this disk being formed with a downwardly extending nub 7 in the middle, which when the closure is placed upon the bottle and tightened up, as hereinafter described, causes a downwardly extending bulge in the rubber pad 5 which enters the neck of the bottle.

The cap is formed with an upwardly extending cylindrical nub or hub 10 on its upper surface for pivotal engagement with the clamping member B, as will be presently described.

The clamping member B is formed preferably with a disk-shaped head portion 11 having a central aperture 12 through which the hub 10 loosely passes, so that the clamping member may be rotated thereon. The said clamping disk 11 is provided with two clamping fingers 13—13 diametrically opposite each other extending from the opposite sides of the periphery of the said disk 11, 80 said clamping fingers being curved outwardly and then reversely curved forming the bowed lips 14 which extend inwardly somewhat farther than the lower edge of the flange 4 of the cap member. These lips 14 are adapted to engage with the annular groove 15 formed in the neck of the bottle under the top bead 2. The width of the groove 16 formed by the reversely curved fingers is somewhat greater than the width 95 of the flange 4 so that the closure member is capable of a slight axial movement but cannot drop out from engagement with the clamping member because the inwardly extending bowed lips form a stop.

On the upper face of the closure member there are formed a plurality of inclined faced cams 17, preferably three in number, each being arc-shaped in plan view and arranged in a circle which is concentric with the closure member. The under face of the disk 11 of the clamping member is formed with a plurality of downwardly extending lugs 18 corresponding in number with the cam surfaces 17, so that 110 when the clamping member is rotated with relation to the closure member, the said

lugs will ride up on the cam surfaces and depress the closure member. When the device is applied to the bottle, the closure member rests on top of the neck and the clamping fingers engaged with the groove 15 on the under side of the bead of the bottle, while the downwardly extending lugs on the clamping member are free from the cam surfaces; and then by rotating the clamping member to cause the said lugs to ride up on the cam surfaces, the closure member will be drawn down tightly onto the rim of the bottle and if it is tightened up as far as it will go it will hold the cap firmly against the top of the bottle. Preferably there are provided stops 19 at the top of the cams to limit the turning movement of the clamping member B.

Preferably the flanged closure disk is stamped out of a piece of metal in such manner as to also stamp out the upwardly projecting hub member 10, and also to form the cam surfaces 17, although this is not essential to the invention. Preferably also the lugs 18 on the clamping member are formed integral with the clamping member.

While I prefer to employ the disk 6 with the projecting bulge 7, said disk may be entirely omitted and my invention broadly covers the device whether used with or without said intermediate metal disk 6.

What I claim is:

1. A bottle closure having a cap member to go over the top of a bottle, and a clamping member rotatably mounted on the upper side of the cap member and slightly movable axially with relation thereto, the clamping member being provided with means for engaging the beaded rim of a bottle, the proximate surfaces of the clamping member and the cap member being provided one with cam surfaces and the other with projections which engage said cam surfaces, whereby the rotation of the clamping member causes the said projections to ride up on the cam surfaces and tightly clamp the said cap to the top of the bottle.

2. A bottle closure having a cap member to go over the top of a bottle, and having a pad therein to engage the top of the bottle, a disk between said pad and the cap having a protuberance which engages the middle of said pad. a clamping member rotatably mounted on the upper side of the cap member and slightly movable axially with relation thereto, and means whereby the clamping member may, when rotated, move the cap member away therefrom to crowd it down tightly against the rim of the bottle and thereby also crowd said protuberance on the disk against the pad and cause the pad to bulge downward into the neck of the bottle.

3. A bottle closure having a cap member to go over the top of the bottle having a flanged rim and a flexible pad seated therein, the cap being provided with an upwardly extending hub on its upper surface, and a plurality of cam surfaces also arranged on the upper surface concentrically about said hub, and a clamping member consisting of a disk having a central hole through which said hub on the closure member extends and in which the said hub is rotatable, the clamping member having peripheral fingers which extend downwardly to engage the bead on the upper end of the bottle, said clamping member having on its under side projections which are adapted to engage with the cam surfaces of the closure member, whereby the cap member is clamped tightly against the top of the bottle.

4. A bottle closure having a cap member to go over the top of the bottle having a flanged rim and a flexible pad seated therein, the cap being provided with an upwardly extending hub on its upper surface, and a plurality of cam surfaces also arranged on the upper surface concentrically about said hub, and a clamping member consisting of a disk having a central hole through which said hub on the closure member extends and in which the said hub is rotatable, the clamping member having peripheral fingers which extend downwardly to engage the bead on the upper end of the bottle, said clamping member having on its under side projections which are adapted to engage with the cam surfaces of the closure member whereby the cap member is clamped tightly against the top of the bottle, the said fingers being bent inwardly in such manner as to serve as a stop to prevent the cap from becoming disengaged from the clamping member.

5. A bottle closure comprising a cushion cap member, and a clamping member rotatably mounted on said cap member and having a slight axial movement with relation thereto, said two members being provided with interengaging cams whereby when the clamping member is rotated with relation to the cap the cap is tightly drawn against the top of the bottle and clamped thereto.

6. A bottle closure comprising a cushion cap member, a clamping member rotatably mounted on said cap member and having a slight axial movement with relation thereto, said two members being provided with interengaging cams whereby when the clamping member is rotated with relation to the cap the cap is tightly drawn against the top of the bottle and clamped thereto, and stops which limit the rotary movement of the clamping member.

In testimony whereof I affix my signature.

FRANCIS H. MILLS.
